PORTABLE POSTHOLE DIGGER

Vaughn O. Gibbens, Santa Ana, Calif.

Application July 21, 1948, Serial No. 39,865

1 Claim. (Cl. 255—19)

1

This invention relates to a portable post hole digger.

It is an object of the present invention to provide a portable post hole digger having its own power plant and which will drill vertical holes regardless of the angle or slope on which the supporting wheels may rest and wherein it becomes unnecessary to level the supporting frame each time a hole is to be drilled and wherein the auger or drill can be adjusted to the right or left of the frame at any desired angle and wherein the digger is carried on a slide which is vertically adjustable on a frame which may pivot relative to the main supporting frame.

Other objects of the present invention are to provide a portable post hole digger which is of simple construction, easy to set up for a drilling operation, self-propelled, durable and rugged, and efficient in operation.

For other objects and for a better understanding of the invention, reference may be had to the following detailed description taken in connection with the accompanying drawing, in which

Fig. 1 is a side elevational view of the post hole digger embodying the features of the present invention and illustrating the manner in which the auger is adjusted longitudinally of the main supporting frame.

Fig. 2 is a top plan view of the post hole digger as viewed on line 2—2 of Fig. 1.

Fig. 3 is a rear elevational view of the digger illustrating the manner in which the auger may be angularly adjusted relative to the lifting frame and to the main supporting frame on which the lifting frame is pivoted.

Fig. 4 is a rear elevational view of the post hole digger with the auger extended into the ground.

Fig. 5 is a fragmentary detail and elevational view of the winch for retaining the auger in its elevated position and for effecting the adjustment of the auger.

Fig. 6 is a fragmentary transverse sectional view of the gear housing to which the auger bit is connected.

Fig. 7 is a sectional view taken through the pivot plate connection of the slide sleeves with the upper end of the vertically adjustable boom or frame.

Fig. 8 is a fragmentary side elevational view of the auger and of an extension thereon for the purpose of digging deeper holes.

Fig. 9 is a longitudinal sectional view taken through the telescoping driving rod extending from the transmission to the auger gear box.

2

Fig. 10 is a transverse sectional view taken on line 10—10 of Fig. 9.

Fig. 11 is a fragmentary sectional view of the connection of the pivot parts with the upper end of the boom and showing a retaining detent engageable with grooves on the upper end of the boom to retain the auger assembly in its laterally adjusted position.

Referring now to the figures, 21 represents a main frame having depending wheel axle 22 with rubber tired supporting wheels 23. On the forward end of the frame is a third wheel 24 which casters. This wheel is removable from the frame in order to permit the digger to be attached directly to a vehicle for the purpose of transport. The wheel 24 is placed on the frame when the digger is put in use. Pull straps 25 serve to connect the digger to a vehicle or tractor draw bar.

On the forward part of the frame, there is mounted a gas engine 26 having a drive sprocket 27 which is connected to a sprocket 28 by a driving chain 29. The sprocket 28 is on a transmission 31 having an output shaft 32 with a universal connection 33 thereon. To this universal connection 33 there is connected a telescopic drive shaft 34 which is connected through a universal joint 35 with a driving gear box 36 which supports an auger bit 37.

The gear box 36 is connected to a transversely extending plate 38 which is connected between upwardly extending pipes 39 which are slidable in sleeves 41 respectively which are connected together by a vertically extending plate 42 having a circular wear plate 43, Fig. 7, engaging with a circular wear plate 44 weldingly secured to a laterally extending sleeve 45. From the plate 44 there extends a pivot pin 46 through wear plate 43 and transverse member 42 and which has a head 47 and a collar 47a for retaining the parts in assembled relation. The pin 46 is first inserted through the plate 43 and transverse member 42, and then through the collar 47a, after which the portion 46a is bent transversely to hold the parts together.

The pivot connection shown in Fig. 7 is slidably connected through sleeve 45 with a top frame bar 48 of an auger supporting frame 49 pivotally connected to the main frame 21 at 51 and adjustable as shown in Fig. 1 in a boom-like manner to raise and lower the auger bit.

The frame 49 is swung on its pivot by an adjusting lever 53 having a detent device 54 cooperating with quadrant 55. The lever is pivoted to the frame 21 at 56 and is connected by link 57 with the frame 49. Stop member 99 is secured to

frame 49 for abutting the rods 39 to limit the forward movement of the slide when the auger is removed from engagement with the ground.

Connected to the member 42 at 58, Fig. 4, is a cable 59 which extends through a pulley block 61 secured to the gear casing 36. The cable extends upwardly over a pulley block 62 on the slide bar 45 on the rod 48 at the upper end of the frame 49. A bracket 64 with hook formations thereon for the purpose of supporting the block 62 extends upwardly and outwardly over the gear casing 36. This cable 59 further extends forwardly to a block 65 on transmission mount 66 and from there to a winch device 67, Figs. 1 and 5. The winch device is carried on an upwardly extending bracket 68 and has a hand crank 69 and a locking lever 70 adapted to engage with either of two diametrically disposed notches 71.

A brake lever 73 can serve to operate brakes 74 pivoted on the frame 21 and engageable with the wheels 23 whereby to retain the frame against movement while the drilling operation is being effected.

The transverse member 48, Figure 7, of the frame 49 has a plurality of longitudinally spaced grooves 75 into which may extend a pin 76, see Figure 11, pressed by a spring 77 and enclosed in a sleeve projection 78 for the purpose of retaining the slide in a laterally adjusted position relative to the frame 49. When it is desired to adjust the slide on the grooved rod 48, the pin 76 is grasped by its handle 79 and pulled outwardly. Thereafter, the slide can be adjusted laterally to position the auger without having to reposition the wheeled frame.

The slide includes transverse member 38, vertically extending rods 39 and a transverse member 81 joining the rods 39 together at their upper ends. This slide with the gear box 36 is adjustable up and down through sleeves 41 as the cable 59 is worked.

The slide, however, can be angularly adjusted in order to locate the auger in a vertical position as when the frame is not on level ground by pivoting the sleeves 41 and their supporting member 42 on pin 46 which is carried by sleeve 45 on the upper end of the frame 49, Fig. 7. This angular adjustment can be effected in the manner shown in Fig. 3.

In Fig. 8, there is shown an auger extension 83 adapted to be connected to the gear box 36 and especially formed on its lower end to receive the main auger bit 37. The extension 83 will be held by the set screw 84 and the auger bit 37 will be held upon the extension by the set screw 85, Fig. 8.

The telescopic drive shaft 34 is adjustable and through the universal joints 33 and 35 will drive in any position to which the parts thereof have been adjusted. The gear box has an input shaft 87 journalled in a sleeve 88, Fig. 6, and with a bevel pinion 89. This pinion 89 meshes with a bevel plate gear 91 fixed by set screw 92 to an output shaft 93 to which the auger is connected and secured by the set screw 84. The gear box 36 has an upwardly extending hook 94 to which pulley block 61 may be attached. This hook 94 is preferably connected to the transverse plate 38 of the slide.

In operation, it will be apparent that the frame

21 can be transported to any location and that with the engine in operation, the auger 37 will be set in motion to effect the drilling of a post hole. The engine drives a transmission which has a gear shift lever 97 whereby the speed of rotation of the auger can be controlled. The auger can thus be operated at several different speeds and as well its rotation may be reversed if necessary to effect the withdrawal of the auger from the hole. 10 The auger is connected to the gear box 36 which is carried on a slide which is adjustable vertically through a connection on a boom 49. This connection can itself be angularly adjusted relative to the boom 48 so that the auger can be extended at an angle. Likewise, this connection can be adjusted along the top of the frame 49 to different lateral positions thereby eliminating the necessity of changing the supporting frame or shifting it from the position to which it has been placed. 20 The auger will be released when the drilling operation starts so that it will feed by gravity. This is done by releasing the locking lever and holding the same out of engagement.

While various changes may be made in the detail construction, it shall be understood that such changes shall be within the spirit and scope of the present invention as defined by the appended claim.

I claim:

25 A portable post hole digger comprising a frame having supporting wheels, a boom pivotally connected to the frame, an adjusting mechanism for adjusting the boom and for retaining the same in its adjusted position, pivot connection means on the upper end of the boom including members angularly adjustable relative to one another, a gear box slidably connected to the pivot connection means and having an output shaft, an auger connected to the output shaft, a power mechanism 30 connected to the gear box of the auger to operate the same, an elevating mechanism for adjusting the gear box and auger on the pivot connection means, said elevating mechanism comprising a cable, said cable being fixed to the pivot connection means, and a hand winch for receiving and adjusting the cable, said pivot connection means including vertically extending sleeves, and a slide provided with laterally spaced rods adjustable in and guided by the sleeves, said boom having a transverse member adjustably connected to said sleeves whereby the pivot connection means and the auger can be laterally adjusted across the top of the boom.
